Attorney

UNITED STATES PATENT OFFICE.

PHILIP C. ACKERMAN, OF MOUNTAIN LAKES, NEW JERSEY, ASSIGNOR TO MERCK & CO., OF NEW YORK, N. Y., A CORPORATION OF NEW YORK.

HEMOGLOBINOMETER.

Application filed August 17, 1923. Serial No. 657,997.

To all whom it may concern:

Be it known that I, PHILIP C. ACKERMAN, a citizen of the United States, residing at Mountain Lakes, in the county of Morris, State of New Jersey, have invented certain new and useful Improvements in Hemo-
10 globinometers, such as are used for testing the blood, and more particularly for determining the percentage of hemoglobin in the blood.

The invention has for its main object to provide a complete and self-containing device of this character which will permit of the same being used immediately when a patient is being examined and independently of a dark room, a special source of light, or other special circumstances or material, and which is of a form suitable for recording the results of the tests made, and of neat 20 and compact size to fit it for filing in a card index cabinet.

My invention comprises a device of this character embodying a colorimetric system in which the different shades of the color are arranged with openings in each field of color so that absorbent paper strips carrying a blood sample to be matched may be passed along the scale of colors to show through the openings in the color scale for the purpose of matching the blood stains with the color scale.

The invention consists of the novel construction, combination, and arrangement of parts which will be hereinafter more fully described and then particularly claimed, and in describing the invention in detail, reference will be had to the accompanying drawing forming a part of this application and wherein like numerals or reference will be employed to indicate like parts throughout the different views of the drawing, in which:

Figure 1 is a front view showing the color scale of the hemoglobinometer.

Figure 2 is a back view showing provision for patient's record of hemoglobin findings.

Figure 3 is a longitudinal sectional view taken on line III—III of Figure 1, showing the front and back sides fastened together along the edges, the pocket formed thereby, and also a strip of absorbent paper inserted therein.

To put my invention into practice, I provide a card-index filing card consisting of

superimposed layers of paper or similar material, preferably consisting of a folded or overlapped single piece of card board, though, of course, I do not confine myself to any specific material. The sides (a) of the paper may be and preferably are permanently fastened along the edges by pasting or other suitable means so as to form a pocket (b) which serves as a receptacle for absorbent paper (c) and also for inserting and guiding the paper along the slot (g) so that portions of it may be passed under and along the scale of colors (e) printed on the front face of the card to show through openings (d) in the color scale for the purpose of matching blood stains (f) on the absorbent strips with the color scale.

The said color scale consists of different shades of the color of blood varying in depth of color to indicate variations in the percentage of hemoglobin in the blood.

In the preferred construction I cut out a small oblong section along the lower edge of the hemoglobinometric aspect of the card to the depth of about $\frac{1}{4}$ to $\frac{1}{2}$ inch, and for the entire length of the hemoglobinometric scale, as shown at (g), which enables the user to more readily manipulate the pocket in its double function as a receptacle for the absorbent paper when not in use, and as a holder and guide for readily inserting and rapidly passing back and forth a strip of paper with a blood stain along and under the perforations in the individual fields of color of the blood color scale while endeavoring to match the specimen with the scale.

In using the apparatus for the purpose of this invention, an absorbent paper is employed, preferably in the form of long narrow strips (c), and I have found it convenient to arrange this paper in perforated sheets so that the strips (c) may easily be detached by tearing for use in absorbing the blood to be tested. When the sheets are not in use they can conveniently be carried in the pocket (b) formed by the superimposed layers of paper, previously described, clean and ready for immediate use in blood testing.

Having fully described my invention, what I claim as new is:

1. A hemoglobinometer and index card comprising an overlapped sheet forming a pocket between the overlapped faces, a grad-

- uated color scale on one face thereof, and a record chart on the other face of said card.
2. A hemoglobinometer consisting of an overlapped sheet forming a pocket between the overlapped portions thereof, a graduated color scale on one of the overlapped portions, and perforations in each of the fields of color of said scale and in combination therewith a record chart on the opposite side.
3. A hemoglobinometer consisting of an index card with a chart for a clinical record on one face thereof, a graduated color scale on the other face, a pocket formed by the overlapping of these two faces, and having a perforation in each color field of the said color scale.
4. A hemoglobinometer consisting of an index card with a chart for a clinical record on one face thereof, a graduated color scale on the other face, a pocket formed by the overlapping of these two faces, and having a perforation in each color field of the said color scale, and having cut out of the lower edge of the face containing the said color scale that substantially oblong section between the said lower edge of that face and the lower margin of the said color scale.
5. A hemoglobinometer consisting of an index card with a chart for a clinical record on one face thereof, a graduated color scale on the other face, a pocket formed by the overlapping of the two faces, the face carrying the said color scale having a substantially oblong segment cut out along the lower edge of said face, between said lower edge and the lower margin of the color scale and to the full width of said color scale but not for the full width of the card.
6. A hemoglobinometer in the form of an index card consisting of superimposed sheets and comprising a graduated color scale, a pocket formed between the said superimposed sheets, and a record chart on one of the sheets.
7. A hemoglobinometer in the form of an index card consisting of superimposed sheets and comprising a graduated color scale, with a perforation in each color field of the said color scale.
8. A hemoglobinometer in the form of an index card, consisting of superimposed sheets, a pocket formed between said sheets, a record chart on one of the sheets, and a graduated color scale on the other sheet.
9. A hemoglobinometer in the form of an index card, consisting of superimposed sheets, a pocket formed between said sheets, a record chart on one of the sheets, and in combination therewith a graduated color scale on the other sheet, and with a perforation in each color field of the said color scale.
10. An improved card index card, in combination with a hemoglobinometer, comprising an overlapped sheet, the overlapping folds being fastened along the side edges so as to form a pocket between the superimposed folds, and in combination therewith a blood-color scale on the one face of said card and a clinical record chart on the other face of said card, and wherein the superimposed fold of said overlapped sheet carrying the said color scale has an oblong segment cut out along the length of the said color scale for a part of the long axis of the card but leaving the side edges of both the upper and lower layers intact.
11. A combined hemoglobinometer and a clinical record chart, in the form of a filing card, having a hemoglobinometric color scale on one side thereof and the clinical record chart on the other side.
12. A filing card having a clinical record chart on one side thereof and a hemoglobinometric color scale on the other side.
13. A filing card having a clinical record chart on one side thereof and a hemoglobinometric color scale on the other side, and a pocket between the two faces of the said chart.
- In testimony whereof I have hereunto signed my name in the presence of two subscribing witnesses.

PHILIP C. ACKERMAN.

Witnesses:

FREDERICK KRAUS,
FRED DITTELBACH.
